UNITED STATES PATENT OFFICE.

EMILY R. RITTER, OF BROOKLYN, NEW YORK.

CHAIR AND CRIB.

SPECIFICATION forming part of Letters Patent No. 560,046, dated May 12, 1896.

Application filed July 17, 1895. Serial No. 556,263. (No model.)

To all whom it may concern:

Be it known that I, EMILY R. RITTER, a citizen of the United States, and a resident of Brooklyn, in the county of Kings and State 5 of New York, have invented certain new and useful Improvements in Chairs and Cribs, of which the following is a specification, reference being had to the accompanying drawings, forming a part thereof, in which similar letters of reference indicate corresponding parts.

This invention relates to chairs and cribs, and the object thereof is to provide a combination chair and crib which may be used as either when desired, and which is simple in construction and operation; and with this and other objects in view the invention consists in the construction, combination, and arrangement of parts hereinafter described and 20 claimed.

The invention is fully disclosed in the following specification, of which the accompanying drawings form a part, in which—

Figure 1 is a side elevation of my combined 25 chair and crib when extended for use as a crib; Fig. 2, a sectional side elevation showing the device folded for use as a chair; Fig. 3, a longitudinal section of the construction shown in Fig. 1; Fig. 4, a plan view of the 30 construction shown in Fig. 2; Fig. 5, an end elevation of the construction shown in Fig. 1, and Fig. 6 a similar view showing the parts folded as in Fig. 2.

In the practice of my invention I employ a 35 chair consisting of a back A, which may be ornamented in any desired manner or in any desired form, and secured to the back A are sides B, also of any desired form, and on the tops of which are placed arms or rests C, which 40 extend outward, as shown in Fig. 1. The back A is provided with legs or supports D, and hinged to the fronts of the sides B are supplemental or auxiliary sides E, provided with legs F, the hinged connection between 45 the sides being shown at G'. As thus constructed the sides E may be turned outwardly and folded backwardly under the arms C, as shown in Fig. 6, in which position my improvement may be used as a chair, or they 50 may be extended, as shown in Figs. 1 and 3, in which position it will constitute a safe and convenient crib. The sides B of the chair

are provided with a bottom G, of wire-mesh or similar material, and the sides E when extended are provided with a bottom frame K, 55 having a bottom portion L, of wire-mesh or similar material, and hinged to the front side thereof is a plate M, which is adapted to be folded vertically, as shown in Fig. 3, and constitutes a foot-board for the crib, or when 60 the parts are placed together, as shown in Figs. 2 and 6, to depend in front of the chair, as shown in said figures, and the bottom frame K is adapted to slide in over the bottom G. When the sides E are extended, the 65 frame K rests upon supports N, connected therewith, and when the sides are folded into the position shown in Figs. 2, 4, and 6 the bottom frame K is taken out and placed over the bottom G of the chair and the mattresses 70 O and O placed together, as shown in Figs. 2 and 6.

Connected with the outer ends of the sides E are hooks P, which are adapted to engage with loops or eyes R, connected with the foot-board M, and hold it in the vertical position shown in Fig. 5, or said hooks may be detached from said loops or eyes and the foot-board may be lowered into the position shown in Figs. 2 and 6. 80

By means of my invention I combine two useful and indispensable articles of household furniture, which may be used as an easy or comfortable chair or seat, or, when desired, converted into a safe, substantial, and comfortable crib, and can easily be placed within the reach of those in medium circumstances. It is so constructed that it requires close scrutiny to discover what it really is, and the 85 cushions or mattresses being separable and removable makes the drawing out of the outer portion an easy matter.

The bottom G may be secured in position in any desired manner, and the sides B and E may be of any desired form or construction, 95 and, as will be observed, when the sides E are folded beneath the arms C the tops thereof are concealed and the entire device is neat and substantial and may be ornamented as required. The cushions or mattresses may 100 also be hinged together, if preferred, and the separate bottoms G and K may also be united in the same manner, and it is evident that other changes in the form, construction, com-

bination, and arrangement of the various parts of my improved combination chair and crib may be made without departing from the spirit of my invention or sacrificing its advantages, and I therefore reserve the right to make such alterations therein as fairly come within the scope of the invention.

Having fully described my invention, I claim and desire to secure by Letters Patent—

The combination of a back A, the sides B secured thereto, arms C on top of said sides, the supplemental sides E, hinged to the front of the sides B and adapted to be extended

outwardly, or folded beside said sides B under the arms, the legs D and F, a bottom G, a frame K having a bottom L and a plate M adapted to be folded to form a foot-board, substantially as described.

In testimony that I claim the foregoing as my invention I have signed my name in presence of two witnesses this 15th day of July, 1895.

EMILY R. RITTER.
